UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR ROCK DRILLS.

Application filed March 6, 1924. Serial No. 697,205.

To all whom it may concern:

- Be it known that I, RUSSELL H. WILHELM, a citizen of the United States, and a resident of Easton, county of Northampton, and 5 State of Pennsylvania, have invented a certain Mounting for Rock Drills, of which the following is a specification, accompanied by drawings.
- This invention relates to fluid actuated 10 percussive machines, but more particularly to a mounting for a rock drill of the hand held type, whereby the forward end portion of the machine may be supported in a new and improved manner.
- 15 It is often desirable to mount a hand held rock drill so that horizontal holes may be conveniently drilled and the operator is not hampered by the weight of the machine. These machines have been heretofore mounted in cradles, which are adapted to be moved back and forth in shells, usually by means of a manually operated feed screw. The handles of these machines have been clamped to the cradles and the forward end 20 25 portions of the machines have been secured to the cradles by separate clamps.
- These clamps however have been found to be objectionable for several reasons. One objection has been that these clamps become 30 loosened after a comparatively short period of time due to the vibration set up in the operation of the machine, and thereafter the machine is not securely held in place in the cradle, with the result that the efficient drilling 35 of the machine is impaired. Another objection to these clamps has been their inability to withstand the hard knocks and usage to which this type of machine is ordinarily subjected and as a result breakage 40 often occurs. Furthermore, some rock drills do not provide sufficient space on their forward end portions to enable a clamp to be secured thereto.
- One satisfactory manner of supporting 45 the front end portion of a hand held rock drill may be obtained by forming a T-shaped projection on the front head of the rock drill, which is guided in guide-ways formed on a cradle. By this means, clamps 50 which have been heretofore used, have been eliminated and an efficient construction produced which is cheap to manufacture, and by which the number of parts on the machine has been reduced.
- Whenever the rock drill is detached from 55 the mounting, this projection is still useful. Heretofore, whenever horizontal holes close to the ground have been drilled by hand held rock drills, the machine is supported on one of the usual lugs on the front head 60 through which the side rods extend, but in time this lug will wear until the front head must be replaced by a new one or the lug will wear to such a point that the weight of the rock drill will be supported on the steel 65 retainer with the added disadvantage of weakening this part. By means of an integrally formed projection formed on the front head the machine may be used for drilling horizontal holes close to the ground 70 and guided and supported upon this projection so that the life of the front head will be considerably prolonged.
- The object of the present invention is to overcome the above mentioned difficulties 75 and to enable a front end portion of a hand held rock drill to be mounted in a new and improved manner.
- Another object of the invention is to produce an improved connection between a 80 front end portion of a hand held rock drill and the mounting therefor.
- Further objects of the invention will hereinafter appear and the invention is shown in one of its preferred forms in the accompanying drawings, in which—
- Figure 1 is a side elevational view of a mounted rock drill of the hand held type, some of the parts being broken away, 85
- Figure 2 is a transverse sectional view 90 taken on the line 2—2 of Figure 1, looking in the direction of the arrows, and
- Figure 3 is a perspective view of the front head of a rock drill shown in Figures 1 and 2.
- Referring to the drawings, A designates a shell which is formed with internal guide-ways B in which the guides C of a cradle D are adapted to extend. The shell A is preferably formed with a cone E to enable the shell to be swivelly mounted on a suitable support. A feed screw F is in engagement with the cradle D adjacent to the rearward end portion of the cradle and is secured to a plate G at one end of the shell A. The plate G is preferably secured to a lug H on the shell A by the bolts J and nuts K. The feed screw F may be provided with a suit-

able handle (not shown) to enable the cradle D to be moved back and forth in the guide-ways B of the shell A.

A lug L is in this instance formed in the 5 cradle D and is preferably formed with a V-shaped notch O which is adapted to receive the handle P of a fluid actuated percussive machine Q of the hand held type. The fluid actuated percussive machine Q 10 in this instance comprises a cylinder or body portion R having a back head S to which is connected the handle P by means of the spring pressed side bolts T. The front head U is also secured to the cylinder R by 15 the spring pressed side bolts T and is adapted to receive the working implement V in this instance in the form of a drill steel which is preferably held in the front head U by the steel retainer W. The steel retainer W is in this instance pivotally connected to the trunnions W' carried on the 20 opposite sides of the front head U. A valve chest X is secured to the cylinder R by the bolts Y and nuts Z and a suitable distributing valve is located in the valve chest for 25 distributing the motive fluid to a hammer piston a which is adapted to reciprocate in the cylinder R for delivering impact blows to the drill steel V.

30 In accordance with the present invention, the front head U is preferably formed with an integral T-shaped projection b at one side of its forward end. The T-shaped projection b is adapted to extend into the guide-way e of the cradle D and have limited longitudinal movement therein, but is prevented from moving in a vertical plane by the 35 guide-ways e. When it is desired to use the rock drill Q for drilling horizontal holes close to the ground, the machine may be 40 removed from the cradle D and the T-shaped projection b will support the machine in this position and prevent wear from occurring on the steel retainer W or other 45 front end parts of the machine.

In order to hold the handle P in the V-shaped notch O, a clamping plate f is adapted to bear against the handle P and a bolt g extends through the plate f and lug L and a coil spring h is preferably located between the lug L and a nut i which is screwed onto the end of the bolt g. In this manner, whenever the piston a strikes against the front head U the force of the 50 blow will be absorbed by the coil spring h and the rock drill Q will be permitted to 55 move longitudinally for a slight distance.

The front end portions of the machines will be guided and supported by the T-shaped projection b and breakage of the front head U or other parts of the machine from the force of the blow of the piston a is eliminated.

I claim:

1. A mounting for a fluid actuated percussive machine comprising the combination of a front end portion of the machine, means formed integrally with said front end portion for supporting said portion, a carriage on which said machine is mounted, 70 said carriage being formed with guide-ways adapted to receive said integrally formed means and to permit said front end portion to slide in the longitudinal plane of the machine but prevent movement in the vertical 75 plane of the machine, means for clamping a rear end portion of the machine to said carriage adapted to permit limited longitudinal movement of the machine relative to said carriage, and a shell on which said carriage is mounted.

2. A mounting for a fluid actuated percussive machine comprising the combination of the front head of the machine, a carriage for said machine having guide-ways, a 80 clamp for a rear end portion of the machine adapted to permit limited longitudinal movement of the machine relative to said carriage, and a T-shaped projection 85 provided on one side of the front head adapted to extend into the guide-ways of said carriage, whereby the front head is permitted to move in the longitudinal plane of the machine but is prevented from moving in the vertical plane of the machine.

3. A mounting for a fluid actuated percussive machine comprising the combination of the front head of the machine, a carriage for said machine, cooperative retaining means formed on said front head and carriage adapted to permit movement of said front head relative to said carriage in the longitudinal plane of the machine but prevent movement in the vertical plane of the machine, means for clamping a rear end 105 portion of the machine to said carriage adapted to permit a limited longitudinal movement of the machine relative to said carriage, a shell for said carriage, and means for moving said carriage relative to said shell.

In testimony whereof I have signed this specification.

RUSSELL H. WILHELM.
